UNITED STATES PATENT OFFICE.

NATHAN W. FLETCHER, OF CHICAGO HEIGHTS, ILLINOIS, ASSIGNOR TO
TURBINE MOTOR TOOL COMPANY, OF CHICAGO, ILLINOIS, A CORPO-
RATION OF ILLINOIS.

TURBINE-MOTOR.

No. 823,210.

Specification of Letters Patent.

Patented June 12, 1906.

Application filed April 27, 1904. Serial No. 205,098.

To all whom it may concern:

Be it known that I, NATHAN W. FLETCHER, a citizen of the United States, and a resident of Chicago Heights, in the county of Cook and State of Illinois, have invented certain new and useful Improvements in Turbine-Motors; and I do hereby declare that the following is a full, clear, and exact description thereof, reference being had to the accompanying drawings, and to the letters of reference marked thereon, which form a part of this specification.

This invention relates to improvements in turbine-motors of that class in which the rotative part or member of the motor is provided with a plurality of annularly-arranged blades or buckets, and the stationary part thereof is provided with a plurality of delivery openings or nozzles operating to direct the series of jets of air or other fluid under pressure against the said blades or buckets.

The apparatus herein shown as embodying my invention is of small and compact form and is designed more particularly for use in connection with or as part of a portable polishing or grinding tool.

The novel features of my invention are, however, applicable to motors or turbines used for other purposes.

As shown in the accompanying drawings, Figure 1 is a view in side elevation of a grinding or polishing machine equipped with a motor embodying my invention. Fig. 2 is a plan view thereof. Fig. 3 is a sectional view thereof, taken upon line 3-3 of Fig. 1. Fig. 4 is a detail section taken upon line 4-4 of Fig. 3. Fig. 5 is a detail section taken upon line 5-5 of Fig. 3. Fig. 6 is a detail side view of the central hollow spindle upon which the rotative part of the engine turns. Fig. 7 is a detail side view of the plug which enters one end of said hollow spindle. Fig. 8 is a view of the endwise-movable actuating member which forms part of the governing device. Fig. 9 is an end view of the part shown in Fig. 8. Fig. 10 is a view of the sliding weights forming part of the governing device separated from the other parts. Fig. 11 is a view of the central valve-rod. Fig. 12 is a view of the handle of the same. Fig. 13 is a perspective view of a cap having a cam-flange through which said rod is given endwise movement.

As illustrated in said drawings, A indicates the stationary or non-rotative body or member of the motor, which is of circular or disk form, and B indicates the rotative member or wheel thereof, which has the general form of a flat disk and is provided at its periphery with a series of curved blades or buckets *b*, which project from the side face of the disk toward the stationary part A and are attached to a supplementary annular supporting-ring B'. Said rotative member B is attached to a central hub B², which turns on a central hollow spindle C, that is secured in a central aperture in the body A and projects therefrom so as to afford a bearing for the central sleeve or hub B².

In the particular construction herein illustrated, wherein the motor forms part of a hand polishing-tool, the stationary body portion A of the motor is supported as follows: D indicates a flat horizontal base plate or block provided with two rigid uprights or supporting-standards D' D². The disk-shaped body part A is provided with a radially-extending lug or projection A', which is engaged with a horizontal pivot-pin D³, secured in the upper end of the standard D'. Said body portion A is also provided at a point diametrically opposite the lug A' with an extension or arm A², which projects radially from the side margin of the body portion A and is adapted for contact with the side face of the standard D², which latter is provided with a slot d, concentric with the pivot-pin D³, and with a clamping-screw D⁴, which passes through the slot d and engages the arm A², so that the body of the motor may be adjusted and clamped in a desired position with respect to the supporting plate or block D. The grinding or polishing apparatus shown is adapted to act on the horizontal surface on which the block or plate D rests and for this purpose is provided with a horizontal shaft E, carrying a grinding or polishing wheel E' and mounted in a rigid supporting-arm E², which is attached to the body portion A of the motor and projects beyond the pivot-stud D³, which forms a fulcrum about which the shaft E moves when the motor is shifted relatively to the plate D to effect adjustment of said grinding-disk E' with respect to the work.

The parts of the grinding or polishing machine heretofore referred to form the subject-matter of a separate application for patent filed simultaneously herewith and form no part of the present invention.

Now referring to the arrangement of the parts by which the air or pressure fluid is directed to and acts upon the buckets *b* of the rotative member or wheel *B* of the motor disk-shaped body *A* of said motor is provided with an annular portion or flange *A*³, Figs. 3 and 5, which project or extend within the annularly-arranged buckets *b*, so that said buckets are located radially outside of said annular part *A*³ and move in a circular path exterior thereto. In the said body part *A* are arranged a plurality of radial ports or passages *F*, which communicate at their inner ends with the interior space or valve-chamber of the central sleeve *C* through the medium of holes or ports in said chamber. The outer ends of said passages *F* are connected with transverse passages *f*, which extend parallel with the central axis of the motor toward the margin of the annular part *A*³ and which communicate with outlet or discharge passages *f'*, Fig. 5, which are arranged obliquely with respect to radial lines of the wheel and which are located in a plane midway between the side margins of the buckets, so that the jets of air or pressure fluid passing from the outer ends of said discharge-passages *f'* act centrally on the several buckets. The inner margins of said buckets are arranged closely adjacent to but out of contact with the smooth exterior cylindric surface of said annular part *A*³, in which the outlet ports or openings *f'* are formed. Air is supplied to the central hollow spindle *C* by means of an air-supply passage *G*, which extends radially of the body part through the arm *A*² hereinbefore described and also through a hollow handle *G'* and communicates with a supply-pipe *G*². At its inner end the passage *G* communicates, through a hole coincident therewith, with the interior or bore of said hollow spindle *C*.

The general operation of the main parts of the motor above described is like that of similar impact-motors, the air or other fluid supplied under pressure through the supply-pipe *G*² passing inwardly through the passage *G*, then through the interior space of the hollow spindle *C* and radially outward through the passages *F* and transverse passages *f* to the exit-passages *f'* and impinge on the faces of the buckets, which are preferably curved, as shown, so as to change the direction of motion of the jets, which latter leave said buckets in a rearward direction with respect to the direction of rotation of the said wheel.

Now referring to the governing or regulating device for controlling the speed of the motor which forms part of my invention the same is constructed as follows: Within the valve-chamber formed by the hollow spindle *C*

is located an endwise-movable valve-rod *H*, which extends through the outer end of said spindle. Said rod *H* is provided with a cylindric piston *h*, which fits and slides endwise within the said valve-chamber and is located at the side of the passages *F* remote from the inlet-passage *G*. Endwise movement of said spindle *H* in a direction to carry the piston *h* over the ports *F* serves to partially or wholly cut off the passage of air to said ports, while endwise movement of the said spindle *H* in the opposite direction serves to open or uncover said ports. Said piston *h* therefore forms, with the passages or ports, a regulating valve. Said spindle *H* is also provided with a second piston *h'*, which likewise fits and slides within the hollow interior of the spindle *C* and is located outside of the passage *G*. From this construction it is manifest that air entering the said valve-chamber through the passage *G* is confined within the space between the pistons *h* and *h'*, and as such air acts with equal pressure on both pistons the valve formed by the piston *h* and the passages *F* is a balanced valve, requiring no more pressure to effect its movement in one direction than the other.

Within a cylindric casing *I*, attached centrally to the disk or wheel *B*, is located an endwise-movable valve-actuating member *J*; the same, as herein shown, having a conical body and a cylindric rod or stem *J'*, which enters or slides within a central bore or guide-opening *c*, formed in the adjacent end of the hollow bearing-spindle *C*. The inner end of said stem *J'* bears against the adjacent end of the rod *H*, which is made conical and engages a conical bearing-recess in said stem *J'*, so that the actuating member *J* may turn on the valve-stem *H* with a minimum of friction. In the drawings the end of the stem *J'* is shown as provided with an antifriction-ring *j'*, of hard metal, for contact with the conical end of the rod *H*. The head or body of the actuating member *J* is provided with a conical recess *j*, Fig. 9. Within said recess are placed two centrifugally-acting weights *K* *K*, each of which is made of triangular form and has an outer oblique edge in contact with the oblique end wall or surface of the conical recess *j*, an inner margin parallel with the central axis of the motor, and an outer face at right angles to said axis and arranged in bearing-contact with a flat bearing-plate *I'*, which is secured to the outer end of the cylindric casing *I*, and the inner face of which is perpendicular to said axis of rotation of the motor.

The central hub *B*² of the bucket-wheel *B* is shown as mounted on the end of the stationary spindle *C* through the medium of ball-bearings, which are formed as follows: On the said hollow spindle *C*, adjacent to the body *A* of the motor, is formed an integral flange *c'*, shaped to form an annular track or bearing-surface *c*² for a series of antifriction-rollers *b'*, 130

which are located between said annular track or bearing-surface, and a like annular track or bearing-surface b' , formed in the adjacent end of the hub B^2 . At the opposite end of said hub B^2 is formed a like annular bearing-surface b' , while the spindle C is provided with an annular flange c^3 , having an annular bearing-surface c^4 , between which and the surface b' are located antifriction-balls b^2 . Said annular flange c^3 and bearing-surface c^4 are formed upon a separate plug C' , which is inserted in the end of and has screw-threaded engagement with the hollow spindle C . Said plug C' being removable from the hollow spindle enables the rotative wheel B to be removed from said hollow spindle when desired. The central guide-aperture c for the stem of the endwise-movable actuating member J is shown as formed within the plug C' . In the operation of these parts the weights K when thrown or moved radially outward by centrifugal action slide outwardly on the inner face of the bearing-plate I' , and their oblique outer margins acting on the oblique bearing-surfaces j^2 of the actuating member J serve to give inward endwise movement to said actuating member, which latter acting on the end of the valve-rod H moves the same endwise and carries the piston h in a direction to cut off the passage of air to the passages F F . Movement of said valve-rod H in the opposite direction or into position to open the passages F F is effected by means of a spring suitably applied to act on said rod. Said spring is herein shown as consisting of a spirally-coiled expansively-acting spring L , interposed between the balancing-piston h' on said valve-rod and a cap M , which is applied to the end of the hollow spindle C . The said cap M is shown as having screw-threaded connection with the end of the hollow spindle C , which extends outwardly beyond the body A of the motor and as being provided with a set-screw m , by which the cap may be held rigidly in place when adjusted to a desired position. By adjustment of the said cap M the tension of the spring L may be regulated as desired. The purpose of the regulating device described is to prevent the motor from turning at a speed greater than that desired and to control the speed of rotation thereof when the motor is doing no work—as, for instance, when the grinding-tool driven thereby is free from contact with the work—it being obvious that by properly adjusting the spring L so that it will yield under the action of the centrifugally-acting weight K when the desired speed is exceeded the passage of air from the interior of the hollow spindle C to the openings F will be cut off to the extent required for supplying the air in quantity necessary to drive the motor at a desired maximum speed; but when the speed of rotation of the motor is reduced through the

resistance afforded by the tool in doing the work then the spring through its expansion will overcome the centrifugal action of the weights and will move the valve-piston h to fully open the valve and give the increased quantity of air or pressure fluid required.

As an additional improvement I extend the valve-rod through the cap M and provide said cap with two exterior flanges M' , having inclined or cam-shaped edges m' , as clearly shown in the perspective view, Fig. 13. I also provide the end of the valve-rod H which projects outside of said cap M with a rigidly-attached double handle or lever N , through which the rod may be turned and the arms of which are adapted to bear upon or engage the said cam-flanges M' M' , being held in contact therewith by the spring L . It follows from this construction that when the lever or handle N is turned by the hand of the operator it will by the action of the cam-flanges against which it bears have the effect of moving the valve-rod endwise in a direction to carry the valve-piston h over the inner ends of the passages F , and thereby close the same.

The handles or levers N on the valve-rod, in connection with the cam-flanges M' or like stationary cam-surfaces otherwise arranged or attached to the body of the motor, serve as a means for positively cutting off the supply of air or pressure fluid to the rotative wheel of the motor, so that the latter may be stopped and started at any time by merely turning the said handle or lever.

The purpose of making the central hollow spindle C as a part separate from the body A of the motor is to enable the said hollow spindle to be made of hard metal, such as tool-steel, adapted to provide a suitably-durable bearing and wearing-surface for the sliding pistons h h' therein and to facilitate the construction of the bearing for the rotative wheel B .

The radial passages F in the body A of the motor may be readily formed by boring radially inward from the exterior of said body and afterward closing the outer ends of the holes made by means of plugs f^2 . The transverse passages f may be likewise formed by boring inwardly from the outer faces of the said body A and closing the outer ends of the holes by plugs f^3 .

The details of construction in the motor shown may be modified in various particulars without departure from my invention, and I do not desire to be limited to the particular details of construction shown except so far as the same may be set forth in the accompanying claims as part of my invention.

I claim as my invention—

1. A turbine-motor comprising a rotative wheel or member having a series of annularly-arranged blades or buckets, a non-rotative member provided with a supply-passage and with a discharge-passage, a valve

- controlling said discharge-passage, a valve-actuating member turning with the rotative member of the motor, a spring applied to move said valve-actuating member in one direction, and a centrifugally-acting governor-weight of wedge form adapted to slide radially on the rotative member and acting on the valve-actuating member to move the same against the tension of the said spring.
2. A turbine-motor comprising a non-rotative and rotative member, said non-rotative member being provided with a central valve-chamber, with a discharge-aperture and with a passage leading from said valve-chamber to said discharge-aperture, and the rotative member having a series of annularly-arranged blades or buckets, and with a central bore in alignment with the valve-chamber in the non-rotative part, a sliding piston in the non-rotative part, which forms with the inner end of the passage leading therefrom, a controlling-valve, an endwise-moving, valve-actuating, member in said central bore of the rotative member, and a centrifugally-acting weight carried by the rotative member and giving endwise movement to the said valve-actuating member.
3. A turbine-motor comprising non-rotative and rotative members, said non-rotative member being provided with a valve-chamber, and with a discharge-aperture, and the rotative member having a series of annularly-arranged blades or buckets, a sliding piston in the valve-chamber for controlling said discharge-aperture, a valve-stem attached to said piston, a balancing-piston on said valve-stem, a valve-actuating member carried by the said rotative member, and a centrifugally-acting weight carried by the rotative member and acting to give movement to said valve-actuating member.
4. A turbine-motor comprising non-rotative and rotative members, the non-rotative member being provided with a discharge-aperture, with a central valve-chamber in communication with the supply-passage and with said discharge-aperture, and the rotative member having a series of annularly-arranged blades or buckets, a sliding piston in said valve-chamber, and a valve-rod connected with said piston and extending to the exterior of said non-rotative member, for operating the said piston.
5. A turbine-motor comprising non-rotative and rotative members, said non-rotative member being provided with a central hollow spindle forming a valve-chamber and which projects beyond the face of said non-rotative member and forms a bearing for the rotative member, with annularly-arranged discharge-apertures, and discharge-passages leading from the said valve-chamber to the discharge-apertures, and the rotative member having a series of annularly-arranged blades or buckets located adjacent to said annularly-arranged discharge-apertures of the said non-rotative member.
6. A turbine-motor comprising non-rotative and rotative members, said non-rotative member having an annular, laterally-extending flange or projection provided with an exterior cylindric surface and discharge-apertures in said annular surface, and said non-rotative member also having a central bearing-spindle which projects therefrom within the said annular projection, and the rotative member having a central hub which is located within said projection and has bearing engagement with said bearing-spindle and is provided at its outer margin with a series of blades or buckets arranged exterior to the said annular projection.
7. A turbine motor comprising non-rotative and rotative members, said non-rotative member being provided with a series of annularly-arranged discharge-apertures, with a central valve-chamber and with delivery-passages leading from said valve-chamber to said discharge-apertures, and the rotative member with a series of blades or buckets arranged adjacent to said discharge-apertures, a sliding piston in said valve-chamber, a valve-rod attached to said piston, and means for giving endwise movement to the valve-rod embracing a cam-surface on the non-rotative member and a radial arm on the said valve-rod adapted to engage said cam-surface.
8. A turbine-motor comprising non-rotative and rotative members, said non-rotative member being provided with a series of annularly-arranged discharge-apertures, with a central chamber and with delivery-passages leading from said valve-chamber to said discharge-apertures, and said rotative member being provided with a series of buckets arranged adjacent to said discharge-openings, a sliding piston in said valve-chamber, a valve-rod attached to said piston, and means for giving an endwise movement to the valve-rod embracing a cam-surface on the non-rotative member and a radial arm on the said valve-rod adapted to engage said cam-surface, said valve-rod being provided with a balancing-piston.
9. A turbine-motor comprising non-rotative and rotative members, said non-rotative member being provided with a series of annularly-arranged discharge-apertures, with a central valve-chamber and with delivery-passages leading from said valve-chamber to said discharge-apertures, and the rotative member with a series of buckets arranged adjacent to said discharge-apertures, a sliding piston in said valve-chamber, a valve-rod attached to said piston, a balancing-piston on said valve-rod, means for giving endwise movement to the valve-rod embracing a cam-surface on the non-rotative member and a radial arm on the said valve-rod adapted to

engage said cam-surface, and a spring applied to move the valve-rod in a direction to hold said arm on the rod against said cam-surface.

10. A turbine-motor comprising a non-rotative member provided with annularly-arranged discharge-apertures, and a rotative member provided with an annularly-arranged series of blades or buckets, said non-rotative member being provided with a central valve-chamber, with a supply-passage communicating with said valve-chamber, and with delivery-passages leading from said valve-chamber to said discharge-apertures and a balanced controlling-valve embracing 15 two connected pistons adapted to slide within said valve-chamber.

11. A rotative motor embracing non-rotative and rotative members, the non-rotative member being provided with a central valve-chamber communicating with a supply-passage and with a delivery-passage leading from said valve-chamber, an endwise-sliding valve-piston in said valve-chamber adapted to coact with the said inner end of said passage to 25 form a regulating-valve, means embracing a centrifugally-acting weight carried by the rotative member for giving endwise movement to the said valve-piston in one direction and an opposing spring for giving movement to 30 said valve-piston in the opposite direction.

12. A rotative motor embracing non-rotative and rotative members, said non-rotative member being provided with a central valve-chamber which communicates with a supply-passage, and with a delivery-passage leading outwardly from said valve-chamber, an endwise-movable valve-rod in said valve-chamber provided with a valve-piston, also with a counterbalanced piston and means for giving 40 endwise movement to said valve-rod, embracing a centrifugally-acting weight which turns with the rotative member of the motor and a spring which acts endwise on said rod in opposition to the said centrifugally-acting 45 weight:

13. A rotative motor embracing non-rotative and rotative members, said non-rotative member being provided with a central valve-chamber and with a delivery-passage leading 50 from said valve-chamber, a sliding piston in said valve-chamber forming with the inner end of said discharge-passage, a regulating-valve, an endwise-movable actuating member arranged centrally of and turning with 55 the rotative member of the motor, centrifugally-acting weights, mounted to slide radially in the rotative member, and acting on an oblique surface of the valve-actuating member to give endwise movement thereto, and a 60 spring applied to act on said valve-piston in opposition to the said centrifugally-acting weight.

14. The combination with the rotative and non-rotative members of a motor, of a regulating-valve comprising a sliding piston and

means for actuating said piston comprising a spring applied to move it in one direction, an endwise-movable actuating member which turns with the rotative member and which is provided with an oblique bearing-surface, 70 and a radially-movable centrifugally-acting weight, said weight being provided with an oblique bearing-surface engaging the corresponding oblique bearing-surface on the actuating member, and having a bearing-surface 75 which slides on a corresponding bearing-surface on the rotative member of the motor.

15. The combination with the non-rotative and rotative members of a motor, of a regulating-valve comprising an endwise movable valve-piston, a centrifugally-acting weight carried by the rotative member of the motor and acting on said piston to move the same in one direction, a spring applied to move the piston in the opposite direction, a 85 valve-rod connected with said piston and extending to the exterior of the stationary member, said stationary member being provided with a cam-surface and the valve-rod with a radial arm or handle adapted to act 90 upon the said cam-surface when the handle is turned.

16. The combination with the non-rotative and rotative members of a motor, said non-rotative member being provided with a 95 valve-chamber, of a regulating-valve comprising a piston adapted to slide in the valve-chamber, an actuating-rod attached to said piston, a balancing-piston on said valve-rod, a centrifugally-acting weight carried by the 100 rotative member and acting on said valve-rod, a removable cap secured to the stationary member, and a spring interposed between the said cap and an opposing shoulder on said rod.

17. The combination with the non-rotative and rotative members of a motor, said non-rotative member being provided with a central valve-chamber, of a regulating-valve comprising a piston which slides in said valve-chamber, an actuating-rod attached to said piston, a balancing-piston on said rod, a centrifugally-acting weight carried by the rotative member and acting on said rod, a removable cap secured to the non-rotative 110 member and provided with an aperture for the passage of the valve-rod, a spring interposed between the cap and a shoulder on the piston, a cam-surface on the non-rotative member and a radial arm on the outer end of 115 the valve-rod adapted to engage the said cam-surface.

In testimony that I claim the foregoing as my invention I affix my signature, in presence of two witnesses, this 13th day of April, 125 A. D. 1904.

NATHAN W. FLETCHER.
